[57] CLAIM

The ornamental design for my amphibious camping and
utilitarian aircraft, as shown.

DESCRIPTION

FIG. 1 is a top front perspective view of an amphibious
camping and utilitarian aircraft showing my new de-
sign;

FIG. 2 is a bottom rear perspective view thereof;

FIG. 3 is a top plan view thereof;

FIG. 4 is a rear elevation thereof; and

FIG. 5 is a side elevation thereof.
